WATER CLOSET COVER

Margarete Basner, 18511 Margareta,
Detroit, Mich. 48219

Filed Feb. 24, 1969, Ser. No. 15,888

Term of patent 14 years

Int. Cl. D23—02

U.S. Cl. D23—68

FIG. 1 is a perspective view of the water closet cover and illustrating my new design;

FIG. 2 is a front elevational view taken substantially along the line 2—2 of FIG. 1;

FIG. 3 is a top or plan view taken substantially along line 3—3 of FIG. 2;

FIG. 4 is a side elevational view taken substantially along line 4—4 of FIG. 2; and

FIG. 5 is a rear elevational view taken substantially along line 5—5 of FIG. 4.

The water closet is shown in broken lines in FIGS. 1 through 4 for illustrative purposes only.

I claim :

The ornamental design for a water closet cover, substantially as shown and described.
